METHOD OF MAKING LEAD ARSENATE.

1,175,565.

Specification of Letters Patent. Patented Mar. 14, 1916.

Application filed October 14, 1911. Serial No. 654,626.

To all whom it may concern:

Be it known that I, LEE SHEPHERD, a citizen of the United States, and a resident of Cleveland, county of Cuyahoga, and State of Ohio, have invented a new and useful Improvement in Methods of Making Lead Arsenate, of which the following is a specification, the principle of the invention being herein explained and the best mode in which 5 I have contemplated applying that principle, so as to distinguish it from other inventions.

The ordinary method of manufacturing lead arsenate has been by a so-called "wet" 15 process, wherein, for example, a soluble arsenate is caused to react with a suitable lead compound so as to precipitate the relatively insoluble lead arsenate. Various modifications in this process have arisen depending 20 upon the character of the salts used, but all are alike objectionable in that solutions more or less dilute in character have to be dealt with, and that the lead arsenate, when finally formed, must be separated or filtered 25 out of a solution with attendant delay. I am aware that it has been attempted to avoid the objectionable features of such wet processes by roasting combining weights of white arsenic and a suitable lead compound 30 in the presence of oxygen so as to produce the lead arsenate at a single operation. A number of difficulties, however, likewise attend this method of treatment, especially if a relatively pure arsenate is desired, and 35 this is more or less essential, at least so far as any admixture of arsenic in the resulting product is concerned.

The object of the present invention, accordingly, is the production of such arsenate 40 by directly combining white arsenic with a suitable lead compound in such a way as to insure the reaction being a complete one, as also to permit the proper proportions of the entering materials to be readily maintained at all times.

To the accomplishment of the foregoing and related ends, the invention, then, consists of the steps hereinafter described and particularly pointed out in the claims.

50 The annexed drawing and the following description set forth in detail various approved methods of carrying out the invention, such disclosed modes, however, con-

stituting but several of the ways in which the principle of the invention may be used. 55

In said annexed drawing:—Figure 1 represents diagrammatically a vertical section of a suitable apparatus for carrying on the present improved process; and Fig. 2 is a plan view, partly in section of a modification in construction.

My improved process is a continuous one and may be briefly described as consisting in burning in gas, under proper conditions, a suitable mixture of either metallic lead or a 65 lead compound, along with white arsenic. Preferably lead sulfid, which is obtainable in practically pure form as the ordinary galena ore concentrate, is employed, not only because it is obviously cheaper than the 70 metal, which has to be smelted from such ore, but also because the sulfur constituent, being combustible, will actually contribute to the maintenance of the temperature required for the reaction between the lead and 75 the arsenic. The latter is the ordinary white arsenic of commerce. While it is preferred to use natural gas for burning the lead and arsenic, on account of its cheapness and heat value, other gases can of 80 course be used.

The white arsenic in commercial form is, of course, already a fine powder, and in order to prepare the lead sulfid ore for use in the present process, it likewise is ground 85 exceedingly fine, such grinding being best done by the air flotation method, which does not require to be described in detail. The ground ore and white arsenic are then intimately mixed in the proper proportion, such 90 mixing being accomplished, for example, in a revolving ball mill; or if desired, the white arsenic may be introduced with the lead ore previously to the latter being ground and the mixing be accomplished incidentally to the grinding of such ore. 95

In order to effect the combustion of the two ingredients just described, the mixture formed thereof is charged into a feeding hopper 1 (Fig. 1), provided with a screw 2 or other feed device, by means of which it may be continuously fed into the air jet 3 of a blow pipe. Air is forced through such jet by a blower 4, while a pipe 5 surrounding the jet so as to form the outer 100 tube of the blow pipe, is connected with 105

a gas main 6. When the gas thus supplied is ignited, the flame encircles the air jet and the escaping air blast which carries the powdered mixture of lead sulfid and white arsenic. The products of the combustion are projected into a combustion chamber 7, which may consist of any material not affected by the intense heat or attacked by the products of the combustion. 10 Thus it may be constructed of iron or suitable brick, but if of the latter, the brick must not contain silica or other compound capable of entering into combination with the lead, so as to be fused. Magnesite or 15 chrome brick are suitable materials for this purpose. A hopper or receptacle opens into the floor of chamber 7, in order to receive any incombustible earthy materials which may be mingled with the lead sulfid ore. 20 Coextensive with the combustion chamber, as it has been termed, is an extension or flue 9, which is shown as being constructed of brick (brick of the kind just described being of course used for this purpose), 25 although it may be of iron, as the combustion chamber proper; or both combustion chamber and this extension, or continuation thereof, may be of brick in the form of a single compartment 10, as shown in Fig. 2. 30 External heat may be applied to this extension of the chamber, as by burners 11, in order to initially raise the same to the proper temperature, or to assist in maintaining such temperature, if it is not desirable 35 to introduce enough gas in the initial combustion step to heat the entire compartment. It is contemplated, however, that enough gas can be thus introduced in installations of the proper size to accomplish the desired 40 result presently to be set forth.

Connected with the furnace, as I shall term the complete combustion chamber, with its extension, is a cooling pipe 12, preferably of metal and of such length and so 45 constructed to cool the fumes resulting from the combustion in the former sufficiently to enable them to be passed through one or more separators or dust collectors 13 in which any solid product may be deposited. 50 A final separation of such product is effected by means of bag filters 14 of well known construction.

The circulation of air through the apparatus is accomplished by means of a fan 55 placed at a suitable point in such apparatus, being shown as located after the bag filters last referred to. The exhaust gases from the filters, whether forced or sucked therethrough are preferably discharged into a stack 16.

The products of the combustion occurring at the entrance to the furnace are probably in the state of vapors and may be considered as consisting of lead arsenate and 60 lead arsenite, or as lead oxid, arsenious

oxid (As_2O_3) and arsenic oxid (As_2O_5), the sulfur in the ore being of course, converted into sulfur dioxide (SO_2), which is a gas. A high temperature, approximating that at which this combustion takes place, is maintained long enough for these vapors, or products of combustion whatever their character, to completely react, the result of such reaction, disregarding the sulfur dioxide, being lead arsenate, where the lead sulfid and white arsenic are mixed together in the proper proportions, and sufficient air is admixed with the gas. This lead arsenate settles in the cooling pipe, the dust collectors and the filter bags, from which it may be removed at intervals. It is an extremely finely divided white powder, very light in gravity and can be used in this condition or be mixed with water to form a paste, if more conveniently handled in the latter form. The term "lead arsenate" as here used, is of course intended to designate the commercial product and not any one specific lead arsenate, commercial lead arsenate usually consisting of a mixture of two chemically different lead arsenates as is well known.

It has already been indicated that in place of lead sulfid, metallic lead or any suitable compound of the metal such as the 90 oxid, carbonate, or basic carbonate may be used, although the advantage in employing the sulfid over any of these should be obvious. The process in hand is also applicable to the making of other metallic arsenates 100 than lead arsenate, such for example as iron arsenate and copper arsenate. Where an oxid, or oxygen yielding compound is employed, the oxidizing of the arsenic is assisted, and instead of depending upon the 105 oxygen from the air or the lead compound for this purpose, some oxidizing material such as niter may be introduced along with the lead and arsenic mixture. The process, likewise is not limited to use of the specific 110 compound of arsenic, viz., white arsenic, that is named; but the higher oxid can be employed if found commercially expedient. The combustion step, furthermore, may be assisted by heating the air which is introduced through the burner. 115

In conclusion it may be remarked that it is quite possible, instead of intermixing the lead compound with the white arsenic, to burn or vaporize these separately and then introduce them into a heated chamber or furnace. This in fact is the arrangement illustrated in Fig. 2, where two hoppers 1 and associated burners 17 are arranged to discharge into the furnace 10. The feeding devices 2 require to be accurately correlated 120 in order to supply the two ingredients for the reaction in just the proper proportion, but otherwise the operation is the same as that previously described. Also in regard 125

to the terms "burning" and "combustion", as herein used, it should be explained that the exact character of the phenomena attending the ignition of the intermingled streams of gas and air discharged from the burner, along with the powdered lead and arsenic borne by such gas and air, is difficult to ascertain. These terms are hence not to be understood as being necessarily employed in a strictly literal sense, but to include either an actual oxidation of any of the ingredients or their simple vaporization.

Other modes of applying the principle of my invention may be employed instead of the one explained, change being made as regards the process herein disclosed, provided the step or steps stated by any one of the following claims or the equivalent of such stated step or steps be employed.

I therefore particularly point out and distinctly claim as my invention:—

1. The method of making lead arsenate, which consists in burning together a combining mixture of a lead compound and an arsenic compound in the presence of air, whereby the products of their combustion are intermingled; and then cooling such products.

2. The method of making lead arsenate, which consists in burning together a combining mixture of a lead compound and white arsenic in the presence of air; whereby the products of their combustion are intermingled; and then cooling such products.

3. The method of making lead arsenate, which consists in burning together a combining mixture of lead sulfid and white

arsenic, both in finely divided state, in the presence of air; and then cooling such products.

4. The method of making lead arsenate, which consists in discharging an ignited combustible mixture of a lead compound, an arsenic compound and a hydro-carbon fuel into a highly heated chamber; and then cooling the products of the resulting combustion.

5. The method of making lead arsenate, which consists in discharging an ignited combustible mixture, consisting of a suitable lead compound, white arsenic and hydro-carbon fuel, into a highly heated chamber; and then cooling the products of the resulting combustion.

6. The method of making lead arsenate, which consists in discharging an ignited combustible mixture, consisting of lead sulfid and white arsenic, both in a finely divided state together with a hydro-carbon fuel, into a highly heated chamber; and then cooling the products of the resulting combustion.

7. The method of making lead arsenate, which consists in discharging an ignited combustible mixture, consisting of lead sulfid and white arsenic, both in a finely divided state, together with natural gas, into a highly heated chamber; and then cooling the products of the resulting combination.

Signed by me this 12th day of October, 1911.

LEE SHEPHERD.
